UNITED STATES PATENT OFFICE.

FLORA BROWN AND ARTHUR SENEZ, OF MARKHAM, TEXAS.

BALLOT-VOTING MACHINE.

1,087,720.

Specification of Letters Patent.

Patented Feb. 17, 1914.

Application filed April 26, 1910. Serial No. 557,785.

To all whom it may concern:

Be it known that we, FLORA BROWN and ARTHUR SENEZ, citizens of the United States, residing at Markham, in the county of 5 Matagorda and State of Texas, have invented new and useful Improvements in Ballot-Voting Machines, of which the following is a specification.

This invention relates to voting machines 10 and the object of the invention is the provision of a simple, cheaply constructed and efficient machine which will record and indicate the number of votes deposited and which will automatically close the receptacle 15 door after a ballot has been deposited and the vote counted.

Further objects of the invention will appear as the specific description which follows is read in connection with the accompanying drawings which form a part of this specification and in which:

Figure 1 is a side elevation with a portion of the casing removed. Fig. 2 is a transverse section on the line 2—2 of Fig. 1. 25 Fig. 3 is a horizontal section on the line 3—3 of Fig. 1. Fig. 4 is a detail side elevation showing the construction of the winding gears. Fig. 5 is a detail sectional view showing the arrangement of the spring 30 supplying drum.

Referring more especially to the drawings, 1 represents a casing upon which is hinged a cover or top 2 having an aperture 3 covered by a transparent member 4. The 35 cover has a suitable space 6 in which cards may be mounted showing the names of the different candidates.

Journalized in suitable bearings 7 mounted on the inside of the casing is a shaft 8 upon 40 which the receiving drum 9 is mounted and directly opposite the shaft 8 in the opposite end of the casing is journalized a shaft 10 upon which the supplying drum 11 is journalized. Wound around the drum 11 is 45 a counting tape 12 which may be provided with a plurality of numbers indicating the number of votes cast. This web or tape is supported beneath the glass covered opening 3 by a bracket 13 50 which permits the web to slide therethrough. The opposite end of the web is connected

with the drum 9 so as to be wound thereupon at each operation of the device.

Secured to the shaft 8 is a relatively large gear 14 which meshes with a pinion 15 55 journalized in a standard 16 carried by the casing. The pinion 15 is rotated by a ratchet crank 17 connected to the lower end of an operating pitman 18 by a link 19. This pitman is slidably mounted in bearings 60 carried by the top of the casing and is supported upon the free end of a leaf spring 20 pivoted upon the bottom of the casing 1. The upper end of the pitman 18 is provided with a thumb button or operating handle 65 21 by which the rod may be depressed against the action of the spring 20 and thus pull upon the link 19 to operate the ratchet crank 17 and turn the pulley 15. This operation results in the rotating of the drum 70 9 in the direction shown by the arrow in Fig. 1 and bringing a new number into view through the glass covered opening 13.

Connected to the pitman 18 intermediate its length is a link 22 whose opposite end 75 is connected to a door 23 on the upper end of a ballot chute 24 which extends down diagonally through the casing and is connected at its lower end to the opposite side of the casing. A suitable door 25 hinged 80 to the side of the casing closes the lower end of the chute and supports the ballots within the chute until it is desired to remove them. When the pitman 18 is operated to wind the tape or web 12 on the 85 drum 9 the door 23 is also operated so as to open the chute and permit the insertion of a ballot. The spring 20 automatically closes the door 23 and returns the crank 17 to operative position, thus placing the device in 90 condition for subsequent operation and preventing the succeeding voters from seeing the ballots which have been placed in the chute.

Having thus described the invention, 95 what is claimed is—

In combination a standard, a shaft mounted in said standard, a wheel fixed on said shaft, a ratchet wheel on said shaft, a pawl crank on said shaft, a relatively long 100 rod, a leaf spring mounted adjacent said standard, and having a deflected portion

disposed at an upward slant, a link connect-
ing said crank and the free end of said leaf
spring, said rod being secured at one end
to the free end of said spring, a guide for
5 said rod, and a button on the projecting
end of said rod, said rod, when depressed,
actuating said pawl-crank.

In testimony whereof we affix our signa-
tures in presence of two witnesses.

FLORA BROWN.
ARTHUR SENEZ.

Witnesses:

GEO. R. BURKE,
T. J. WALKER.
